BREATHING DOLL

Georgene Averill, New York, N. Y.

Application August 23, 1933. Serial No. 686,460

2 Claims. (Cl. 46—40)

This invention relates to dolls and has for its object to so construct a doll that when pressure is applied to the body air will be expelled from openings in the head, such as the mouth or nostrils, in a manner to simulate breathing.

A further object is to provide a doll with a reservoir containing a volume of air to be expelled, and with means to insure that particles of the body filling material will not gain access 10 to said reservoir and be expelled with the air.

A further object is to so construct the doll that a slight compression of any part of the body below the head will cause expulsion of the air.

15 To the above ends the present invention consists of a doll having a compressible body portion, a hollow head portion having openings leading therefrom at the mouth and nose, and a rigid diaphragm or partition at the neck portion 20 provided with an opening connecting the head and body portion whereby to permit the passage of air through the diaphragm; and it further consists of the devices and combination of devices which will be hereinafter described and 25 claimed.

The present invention is illustrated in the accompanying drawing, in which—

Figure 1 shows the doll in front elevation, a portion of the body covering being removed to 30 better show the construction;

Figure 2 is a very much enlarged view as compared with Figure 1, and illustrating the torso and head in vertical section; and

Figure 3 is a vertical sectional view showing a 35 modified form.

Similar reference characters will be employed throughout the specification and drawing to designate corresponding parts.

In the drawing 1 indicates the head which, as 40 shown in Figures 2 and 3, is made hollow of some suitable plastic material which may be molded to shape and will upon setting become relatively hard. The hollow portion of the head forms a chamber or air reservoir 2 which in normal 45 condition will be filled with air, not under compression however. A neck portion 3 is provided having an external groove 4 and which upon the inner surface forms a shoulder 5. The body covering 6 is made of a relatively thin, flexible 50 textile fabric, coated in order that it may present a pleasing appearance, and to prevent the escape of air which may be contained therein, excepting into the chamber 2 and out of the head, as will be hereinafter described. The upper end 55 of the body covering 6 is open and receives the

neck portion of the head to which it is attached in the groove 4 and to the outer surface of the depending neck portion in any suitable manner, as by an adhesive.

The torso 7 and the legs 8, as well as the arms 60 9, will all be covered with the same thin, flexible air-proof material 6. The hands 10 will be preferably formed of the same material as the head and may be secured to the lower ends of the arms 9 by an adhesive or by any other suitable 65 means. Suitable feet 11 will also be provided of the same construction as the rest of the body of the doll.

The entire body from the neck to the feet is 70 filled with some suitable fibrous material 12, such as kapok, which will be employed in a suitable quantity to fill out and give shape to the body, including the arms and legs, but loose enough so that a slight pressure will suffice to compress any part of the body, thus expelling 75 the air therein, and to provide for automatic expansion to take in air. This kapok filling covered by the thin, coated fabric 6 gives form to the body portion, and when covered externally with a flesh colored coating will strongly simulate 80 the texture of the skin of the body of a young child.

At the neck portion a rigid diaphragm 13, circular in form, is seated against the shoulder 5 and firmly held therein by any suitable means, 85 as for instance, cement. At its center this diaphragm is provided with a circular opening 14, through which passes the tubular extension 16 of an inverted funnel 17, it being held therein by the over-turned flange 18 and washers 19 and 90 20. The funnel 17 near its lower open end is provided with a filtering screen 21 held therein by means of a metallic band 22. The diaphragm 13 and the screen 21 will insure that the filling 12 will not escape into the head 2, nor will the air 95 passing from the torso to the head carry with it any of the filling.

The head is provided with a mouth opening 23 and nostrils 24 positioned as shown in Figure 1 to correspond with the simulation of the mouth and nose on the face of the doll. A sleeping eye construction 25 may be employed, as shown in Figures 2 and 3, if desired, but in itself forms no part of the present invention and need not be 100 described as it is a device of common construction in dolls.

In Figure 3 a modified form is shown in which to the upper end of the tubular portion 16 of the funnel and above the partition or diaphragm 13 a tubular extension 26 is fitted to the tubular 105 110

portion of the funnel 17 and curved forward at its upper end, as indicated at 27, so that the air expelled will be directed to the openings in the mouth and nose.

5 In operation, assuming that the torso has been expanded to its normal condition, the chamber and the kapok filled body will contain more or less air, not under pressure however. A slight compression of the body covering at any point
10 will cause the air to flow from the body into the head and out of the openings, thus simulating breathing.

I claim:—

1. A breathing doll having a hollow head provided with openings at the mouth and nose por-

tions of the face, a soft compressible body formed of relatively thin, flexible, coated, air-proof fabric connected to the head at the neck, a resilient fibrous packing within the body portion, a rigid circular partition separating the head and body, 80 an opening therein, an inverted funnel suspended through said opening having at its lower end a screen permitting the passage of air through said partition.

2. A breathing doll having the construction set forth in claim 1 in which the funnel is connected to a forwardly curved, tubular extension located within the head.
